1 Claim

ABSTRACT OF THE DISCLOSURE

A mold for the forming of a contoured ceiling tile by the vacuum molding technique. A frame is prepared having the desired contour and this is immersed in a tank containing a liquid pulp slurry. A vacuum is pulled on one side of a contoured screen resulting in a buildup of wet pulp fibers on the reverse side of the screen. The pulp fibers, when dried, form a contoured ceiling tile to provide a ceiling system with a noticeable third dimension. The screen is formed by placing a plurality of small tubes side by side. The open ends of the tubes form a screen-like structure on which the wet pulp fibers can build up to form the ceiling tile. The reverse end of the open tube structure rests on a perforated design plate which is contoured to the desired ceiling tile design.

**CROSS-REFERENCE TO RELATED
APPLICATION**

The invention herein described is directed to an improved mold structure for use in carrying out the process set forth in copending application Ser. No. 664,074, filed Aug. 29, 1967.

BACKGROUND OF THE INVENTION**Field of the invention**

The invention is directed to a mold for vacuum forming contoured ceiling tile. The invention contemplates specifically the use of a readily adjusted mold contour.

Description of the prior art

The majority of ceiling systems currently in use are the single plane or two-dimensional ceiling system which provides a flat ceiling structure. Recently there has been a trend towards the development of a ceiling system which adds a third dimension, height, to the ceiling.

The invention herein contemplates the use of a specific die for vacuum forming of contoured ceiling tiles. Through the use of a perforated design plate and a plurality of side-by-side tubes resting on the design plate, a specific die structure is provided for forming the contoured tiles. The ends of the side-by-side tubes form the surface upon which the buildup of wet pulp fibers is secured with the vacuum forming process. This contour at the end of the side-by-side tubes is formed by the particular design for the perforated design plate on which the tubes rest. By readily interchangeably substituting different designs of perforated design plates the contour of the outer ends of the side-by-side tubes is readily changed to provide different contours for the ceiling tiles.

SUMMARY OF THE INVENTION

This invention is directed to a mold used for vacuum forming a contoured ceiling tile from a wet pulp fiber slurry. The mold with the desired contour is inserted in a slurry bath and, by utilization of a vacuum, the fibers are deposited on the surface of the mold to form the contoured ceiling tile. Drying of the fiber material results in a rigid tile structure that will hold its contoured shape. The surface of the mold that forms the contoured ceiling

2

tile is composed of a plurality of side-by-side tubes whose open ends form a screen-like structure. The tubes rest upon a perforated design plate which is bent to form the desired contour for the ceiling tile. The tubes readily conform to the contour of the perforated design plate resulting in this particular contour being imparted to the open ends of the tubes. By changing only the perforated design plate, it is possible to secure a wide range of interchangeable designs.

10 BRIEF DESCRIPTION OF THE DRAWING

The figure is a perspective view, partially exploded, of the vacuum mold used with the process as set forth in copending application S.N. 664,074.

**15 DESCRIPTION OF THE PREFERRED
EMBODIMENT**

In the preferred embodiment set forth in the figure there is shown the perforated support plate 2 which separates the suction box 4 from the mold chamber and assembly 6. The suction box is connected to a filtrate drain and vacuum connection 8, and this assembly is conventional in the vacuum forming art. The support plate 2 carries the mold assembly 6 and has a plurality of perforations 10 to permit the forming of a vacuum inside the mold cavity and to permit the passage of water to the filtrate drain.

The mold assembly consists of a contoured, perforated design plate 12 supporting a variable contour mat 14. The contour mat 14 is composed of a plurality of fine tubes. The tubes are placed in an adjacent side-by-side relationship and are retained in their side-by-side relationship by clamping channels 18.

The contour surface upon which the slurry solids collect is formed by the open ends of the fine tubes held intimately aligned and erect by the clamping channels. The open end arrangement of the tubes form in effect a screen-like structure. The other ends of the tubes rest on the perforated design plate whose contour matches that of the desired design. The tubes, resting upon the perforated design plate, then assume a facsimile of the contours of the plate, and the degree of registration depends for the most part on the diameter chosen for the tubes.

In order to change the mold design we remove the mold chamber and assembly 6 from the suction box 4. The clamping channels 18 are released to remove the constraining force which holds the adjacent fine tubes in position. The perforated design plate can be removed and a substitute plate having a different design put in position. The tubes are then pressed into contact with the substitute plate and then are reclamped in position by the clamping channels. The unit is then reassembled to the suction box, and the mold is now ready to be used to form a new design. The design plate can be made of any porous material that is capable of supporting the tubes, yet passing water and air.

Depending upon the vacuum used, the surface of the finished ceiling tile may become pimpled if the slurry solids are pulled partly into the bores of the individual tubes. Further, a membrane permeable to liquids can be interposed between the solids and the end of the tubes. If a number of the tubes are replaced by pins or rods, the slurry solids will collect around these projections and will form either acoustic or ventilating holes depending on the rod length. The tube diameters may be varied depending on the surface texture desired. Also, the tubes need not be round but could be square, hex-shaped, etc. in cross-section.

The mold is used to form the ceiling tiles in the same manner as set forth in the aforementioned copending application Ser. No. 664,074. The great advantage of this

particular mold design is its adaptability to various designs.

It will be obvious to those skilled in the art that various changes may be made without departing from the spirit of the invention and, therefore, the invention is not limited to which is shown in the drawing and described in the specification, but only as indicated in the appended claim.

What is claimed is:

1. A mold for forming pulp articles by deposition from liquid pulp slurry, said mold comprising a closed box means connected to a source of suction, said box means having a perforated wall, a perforated contoured plate means resting upon the perforated wall and having a design identical with that of the article to be formed, a plurality of separate tubes in side-by-side relationship with one end resting upon the perforated design plate means,

and means restraining said tubes in their side-by-side relationship, the other end of the tube means forming a means for the deposition of the fibers from the liquid pulp slurry to form a decorative ceiling tile.
